UNITED STATES PATENT OFFICE.

WARREN LAWSON KLUTTZ, OF BIRMINGHAM, ALABAMA.

BLAST-FURNACE TOP.

Application filed August 4, 1920. Serial No. 401,102.

To all whom it may concern:

Be it known that I, WARREN LAWSON KLUTTZ, a citizen of the United States of America, residing at Birmingham, in the county of Jefferson and State of Alabama, have invented certain new and useful Improvements in a Blast-Furnace Top, of which the following is a specification.

My invention relates to a top structure for metallurgical blast furnaces of the type in which the distributing mechanism co-operates with a skip or equivalent hoist to distribute the stock charges on the large gas seal bell to the end that the distribution of the stock in the furnace shall be that best suited for the desired furnace operation.

The chief object of my invention is to improve the manner of the distribution of the stock in the furnace by so adapting the distributing mechanism that the stock will fall on the large gas seal bell in spaced piles occupying segments thereof with the material of each segmental pile varying in size in different radial zones of the segment. In other words, considering each segment of the furnace individually into which a stock pile falls, it will be found that the coarser particles will occupy the zone along one radial edge of such segment while the finer particles will occupy the zone along its other radial edge, and the stock in the intervening space will graduate in radial zones with approximate uniformity from coarse to fine. This being characteristic of each pile or segment of the stock, the resultant charge, considered as a whole, will present a successive series of radial segments, the stock in each series varying from coarse to fine particles, thus causing the blast to penetrate more uniformly through the stock from center to circumference of the stack and by this arrangement I avoid the disadvantages of distributing the coarse or fine stock about the lining, thereby causing the blast to travel practically entirely through the center or up along the lining of the furnace.

As a preferred means for accomplishing this novel distribution I utilize a peculiarly constructed distributing chute having a central top intake and a curved body terminating in a discharge opening lying in a ra-

dial plane. By this arrangement the stock is directed downwardly and discharged substantially at right angles to a radius of the large bell, thereby causing the fine particles to fall in a radial zone adjacent to the discharge end of the spout while the coarser particles will fall in a radial zone farthest from the spout. It should be understood that any other mechanical means for accomplishing this distribution may be substituted within the scope of my invention.

Another feature of my invention is the simplification of the means for advancing the distributing spout step by step in co-ordination with the operation of the skip hoist or equivalent loading mechanism. My preferred step by step drive for the spout involves the provision of an automatic clutch so co-ordinated with each top pulley of the skip hoist or equivalent element that it will have a reversible rotation. This clutch, or where a double skip is used, these clutches are driven only during the upward travel of their respective skip cars and the clutches transmit their motion through suitable sprockets or equivalent driving means to the gearing which rotates the distributing spout and if desired a differential selective drive may be interposed to vary the angles through which the spout is advanced each step. In this manner the spout may be caused to make four or six discharges during each complete rotation.

My invention involves the novel details of construction and arrangements of parts which are hereinafter more particularly described and claimed and which are illustrated in their preferred embodiment only in the accompanying drawings which form a part of this specification, and in which:

Fig. 1 is a sectional view through a furnace top showing the super-structure in elevation with the hood broken away to show the distributing spout in elevation.

Fig. 2 is a plan view of the distributing spout taken on the line 2—2 of Fig. 1 with the hood removed.

Fig. 3 is a detail plan view of the step by step drive mechanism for the distributing spout; and

Figs. 4 and 5 are detail views showing the

automatic driving clutch for the step by step driven mechanism in partial section and in elevation, respectively.

Fig. 6 is a vertical sectional view corresponding to Fig. 1 taken at right angles thereto, the view showing the spout in elevation and omitting the bell operating mechanism.

Similar reference numerals refer to similar parts throughout the drawings.

In the preferred embodiment of my invention illustrated, I show a typical blast furnace 1 having a large gas seal bell 2 seated against the lip ring 3 of the hopper 4 which is attached to the top brackets 5 of the stack. A hood 6 is mounted on a base ring 7 and at its upper end carries a flanged casting 8 which supports the race 9 for the balls 10 on which the ball gear ring 11 turns. A top hopper 12, supported by channels 13 of the main frame 14, carries at its lower end a cast ring 15 which seats with a close turning fit above the gear ring 11.

The large gas seal bell 2 is operated by a rod 16 which passes up centrally through the hood 6 and hopper 12 and is controlled by a lever 17, which at its outer end has a dependent piston rod 18 carrying a piston working in the cylinder 19. Within the upper hopper 12 I provide as a suitable means to seal the furnace, when the big bell is open, a small gas seal bell 20 through the center of which the rod 16 passes with a sliding fit and this bell 20 is operated by links 21 disposed on opposite sides of the rod 16 and connected to the lever 22 which is operated by a piston rod 23 having a piston operating in the cylinder 24. These beams 17 and 22 are mounted on pivotal bearing brackets carried by the main frame 14 and they are typical of any suitable means for independently operating the upper and lower bells. At the base of the upper hopper 12 is a downwardly tapering lip ring 25 having at its base a seat adapted to be engaged by the bell 20, when the latter is lowered, to seal the top opening of the hood 6. This lip ring overhangs the open top of the stock distributor which is carried by and rotatable with the gear ring 11.

The stock distributor comprises a spout having an upper section 26 and a lower section 27 formed preferably by flanged castings which are bolted together, the upper casting being flanged and bolted to the ring 11. The upper chute 26 has a circular top opening with which the rod 16 is concentric and it is provided with a guide 28 through which the rod 16 passes. This arrangement permits the chute to rotate freely about the rod 16. The lower flanged end of the upper section lies in the plane approximately 45° to a horizontal plane and the lower spout section from its point of connection to the top section 26 is curved downwardly and

twisted laterally so that its discharge opening will lie in a vertical radial plane through the hood. It will be observed that the opening through the spout changes gradually in shape from circular in cross section at its top intake to an ellipse at its discharge end, the long axis of the ellipse being disposed radially and horizontally and having such length that there is an approximately even distribution of the stock along a radius of 75 the large bell and its hopper.

The step by step drive for the spout comprises a pinion 29 which meshes with the teeth on the rear ring 11 and is fast on a vertical shaft 30 mounted in suitable bearings and carrying at its upper end a bevelled gear 31 which meshes with a bevelled gear 32 on a counter-shaft 33 mounted in suitable bearings in the top frame 14. This shaft 33 carries at its ends two sprocket wheels 34 and 35, both loose thereon and connected respectively by sprocket chains 36 and 37 to the different sized sprocket wheels 38 and 39, which are fast on a countershaft 40. The sprocket wheels 34 and 35 carry clutch elements 41 adapted respectively to interlock with a clutch element 42 which is keyed on the shaft 33. Where the apparatus is designed to coordinate with a double skip, the clutch elements are arranged at opposite ends of the shaft and are operated by a common rigging 43 which causes only one of the gears 34 and 35 to be locked to the shaft 33 at a time. The shaft 40 near each end carries similar sprocket gears 43 and each of these gears is driven by a sprocket chain 44 from its respective sprocket gear 45. One of these sprockets 45 is provided for each skip 52. Each sprocket 45 is mounted to turn freely on its shaft 46 upon which the main sheave wheel 47 of its respective skip is keyed. Rotatable with each sprocket 45 is an outer clutch ring 48 which surrounds a ratchet wheel 49 keyed on its respective shaft 46. The teeth 50 on the ratchet are tapered or wedge shaped and upon each tooth is mounted a roller 51. This roller when at the base of the tooth will clear the inner surface of the ring 48 and the roller will stay at the base of the tooth while the shaft 46 is turning with the sheave as the skip descends. When the skip starts upwardly the reverse drive of the sprocket 50 will cause the rollers to ride up the teeth 50 and wedge against the ring 48 and thus form an automatic clutch interlock for its sprocket 45 so that the latter starts to drive the distributing spout. In this manner the sprockets 45 alternately drive the spout advancing it step by step through the predetermined angular rotation according to the ratio of the sprockets 38 and 34, and 39 and 35, which vary and are selectively brought into service by the operation of the clutches 42.

In operation, as the skips ascend and descend their respective automatic clutches 48 and 49, become alternately effective and drive through the transmission described to 5 advance the spout one step for each skip load hoisted. At the same time, and in the manner well understood, the upper bell is held in raised position and the successive skip loads of stock fall into the upper hopper 12 and 10 are directed through the distributing spout so that they fall upon the large bell 2. In each of these piles the fine material lies radially adjacent to the spout and the coarse material in a zone remote from the spout. 15 In Fig. 2 a skip load of stock is shown distributed on the segment of the big bell 2 and lip ring 4 which is subtended by the arc indicated by the dotted line 53. It will be observed that this charge of stock 20 is shown subdivided in an illustrative manner by radial lines into three radial zones marked 54, 55 and 56. The zone 54 farthest from the discharge end of the spout contains the coarse particles of stock of approximately uniform size from the inner to the outer edge of the zone. In like manner 25 the zone 56 contains the fine particles, and zone 55 the particles of intermediate sizes. As the spout is moved by each approaching 30 skip the piles of stock are distributed circumferentially about the bell in segments approximately equal to 53, and in each segment will occur the radial stratification of the stock into the series of zones 54, 55 and 35 56. After the desired amount of stock has been accumulated in different piles upon the large bell 2, the upper gas seal bell 20 is lowered and the large bell 2 dropped so as 40 to discharge the stock into the furnace. As it falls into the furnace the stock will preserve approximately its relative degree of separation into radial zones of coarse and fine so that the stock in the furnace will be divided into segmental zones, each comprising 45 a series of zones grading from coarse to fine stock, and in each zone the size of the particles will be approximately uniform from the center to the lining of the furnace, thus permitting a uniform passage of air 50 throughout the zone.

The means for carrying the foregoing objects into effect may be widely varied without departing from the spirit and scope of my invention.

55 What I claim, is:—

1. In a blast furnace top, the combination with the main bell and its hopper, of an intermittently rotatable distributing means adapted to discharge the stock in a direction substantially at right angles to a radius of the hopper at the discharge end of 60 said distributing means.

2. In a blast furnace top, a main bell, a 65 hopper therefor, a distributor rotatable above the hopper and having a downwardly

inclined laterally twisted discharge chute with outlet opening disposed substantially radially of the hopper to cause the material to flow into the hopper in a direction substantially at right angles to a radius of the 70 hopper intersecting said chute's discharge outlet, and means responsive to the hoisting of stock to move the distributor intermittently step by step.

3. In a blast furnace top, the combination 75 with the main bell and its hopper, of a rotatable distributing chute having a circular top lying in a horizontal plane and a curved body gradually changing downwardly in cross section from a circle to an ellipse, said body being downwardly inclined and laterally curved to dispose its elliptical discharge end in a radial plane of the hopper with the long axis of the ellipse disposed substantially horizontally. 80

4. In a blast furnace top, means for admitting and distributing stock comprising a rotatable distributing element, mechanism for advancing said element step by step comprising a reversible hoist operating mechanism, automatic clutch means driven by the hoist only throughout one direction of its movement, and motion transmission means for driving said rotatable distributing element from the clutch means. 85

5. In a blast furnace top, means for admitting and distributing stock comprising a rotatable distributing element, mechanism for advancing said element step by step comprising a reversible hoist operating mechanism, automatic clutch means driven by the hoist only through one direction of its movement, and a differential selective drive means for transmitting motion from 90 said clutch to said rotating element. 105

6. In a blast furnace top, a reversely rotatable top hoist sheave wheel, a clutch element rotatable with the wheel and comprising wedge shaped teeth, rollers mounted on said teeth, a secondary clutch element comprising an annular surface surrounding the toothed element and adapted to be interlocked therewith by the wedging action of 110 said teeth on the rollers as the sheave wheel turns in one direction, transmission means driven by said secondary clutch element, a large gas seal bell, a hopper therefor, a secondary gas seal means, a hopper superimposed on the first mentioned hopper, and a rotatable distributor between said hoppers driven step by step by said transmission means. 115

7. In a blast furnace top, the combination 120 with a double skip hoist mechanism comprising a top sheave wheel for each hoist, of an automatic clutch controlled and driven by each wheel as it rotates in one direction only, a countershaft, a driving connection from each clutch to said shaft, a second countershaft, differential driving connec- 125 130

tions between said countershafts, a clutch mechanism to throw said driving connections one at a time into operation, a large gas seal bell, a hopper therefor, a small gas seal bell, a hopper therefor superimposed on the first mentioned hopper, rotatable stock distributor interposed between the

hoppers, means operated by said driven countershaft for rotating said distributor step by step, and means to operate the bells. 10

In testimony whereof I affix my signature.

WARREN LAWSON KLUTTZ.
